UNITED STATES PATENT OFFICE

JOHN SETH, OF NORTH PLATTE, NEBRASKA.

STAY-BOLT.

1,059,573.

Specification of Letters Patent.

Patented Apr. 22, 1913.

Application filed September 29, 1911. Serial No. 651,968.

To all whom it may concern:

Be it known that I, JOHN SETH, a citizen of the United States, residing at North Platte, in the county of Lincoln and State 5 of Nebraska, have invented new and useful Improvements in Stay-Bolts, of which the following is a specification.

My invention relates to stay bolts.

An object of my invention is to provide 10 a stay bolt of such construction as will prevent the crown sheet of a boiler from warping and sliding up on itself.

Another object of my invention is to provide 15 a stay bolt which is adapted to keep the crown sheet of a boiler from warping or being otherwise displaced and at the same time be easy to attach or detach.

A further object of my invention is to provide 20 a stay bolt which is simple and easy to manufacture and it is thought that the same can be sold at a very low cost.

With the foregoing and other objects in view my invention relates to such details of construction and in the arrangement and 25 combination of parts as will be hereinafter fully described and specifically pointed out in the appended claims.

In describing my invention in detail reference will be had to the accompanying 30 drawings wherein like characters denote like or corresponding parts throughout the several views and in which—

Figure 1 is a side elevation of a stay bolt, showing my attachment applied thereto. 35 Fig. 2 is a perspective view of a stay bolt. Fig. 3 is a bottom view of the attachment which is applied to the stay bolt. Fig. 4 is a side view of the attachment which is applied to the stay bolt.

It is well known that the crown sheet of 40 a boiler becomes very hot and in becoming so and being cooled the same becomes warped and tends to slide up on the stay bolt. My invention is thought to overcome 45 this defect.

In the drawings I have shown the top of a boiler 1 and a crown sheet 2, the two being connected by means of the stay bolt 3. The stay bolt 3 has a head portion 4 formed 50 thereon.

Disposed upon the stay bolt 3 which is screw threaded as shown at 5 is a nut 6 which serves a purpose that will be herein-after fully described. I also provide a sleeve

7 which has the cut out portions 8 formed 55 therein. The nut 6 is adapted to be screwed down until it engages the top of the sleeve 7 whereby said sleeve is held securely against the crown sheet and will prevent the same from sliding up on the stay bolt. By hav- 60 ing the cut out portion 8 formed in the sleeve 7 I get a complete circulation of water in the boiler which is so essential in the working of the same.

It will be readily seen that the foregoing 65 arrangement of elements prevents the crown sheet from sliding up on the stay and it is thought that the advantages and novel features of the same will be appreciated.

I desire to lay great stress upon the sim- 70 plicity of my attachment as the same can be manufactured at a very small cost.

I desire it to be understood that I may make slight changes in the construction without departing from the spirit of my in- 75 vention provided such changes fall within the scope of the subjoined claims.

Having thus fully described my inven- 80 tion what I claim as new and desire to secure by Letters Patent is:—

1. In a device of the character described, the combination with a boiler having stay bolts connecting the crown sheet and the top thereof of a sleeve, the interior of said sleeve being of greater diameter than said 85 stay bolt and adjustable thereon, the said sleeve having a plurality of elongated slots formed in the lower extremity thereof, and a nut mounted on said stay bolt and adapted to rest upon the upper end of said sleeve, 90 the said nut adapted to hold the said sleeve against said crown sheet, thereby preventing the same from sliding upon said bolt, sub- stantially as and for the purpose set forth.

2. In a device of the character described, 95 the combination with a boiler having stay bolts connecting the crown sheet in the top thereof of sleeves slidably mounted upon said stay bolts and nuts upon said stay bolts adapted to engage the upper end of said 100 sleeve and hold it in engagement with the crown sheet, whereby said crown sheet is prevented from sliding upon said stay bolt.

JOHN SETH.
